UNITED STATES PATENT OFFICE.

AUGUST G. LIEBMAN, OF CHICAGO, ILLINOIS, ASSIGNOR TO VIGNOLE'S RAIL CHAIR COMPANY, A CORPORATION OF DELAWARE.

RAIL-CHAIR AND RAIL-FASTENING.

1,126,516.

Specification of Letters Patent.

Patented Jan. 26, 1915.

Application filed August 22, 1914. Serial No. 858,042.

To all whom it may concern:

Be it known that I, AUGUST G. LIEBMAN, citizen of the United States, residing at Chicago, in the county of Cook and State 5 of Illinois, have invented certain new and useful Improvements in Rail-Chairs and Rail-Fastenings, of which the following is a specification.

This invention relates to track appliance, 10 and particularly to chairs for supporting rails.

The primary object of the invention is to provide a chair which will not only support the rail against thrusts, but which will hold 15 the rail securely to treated ties during track laying without damage to said ties and without re-spiking.

A further object of the invention is to provide means whereby the rail and chair 20 may be held temporarily engaged with a tie, said means, however, being readily disengaged from the tie to permit the chair to be elevated or laterally shifted with the rail.

A further object of the invention is to 25 provide a rail fastening which performs the dual function of a rail bracing and tie engaging member, and in this connection to provide a base plate with which the tie and rail engaging members will co-act so as to 30 rigidly engage the rail on each side thereof and hold it in proper position.

A further object of the invention is to 35 provide means for temporarily fastening the rail to a tie which will permit the resurfacing of subgrades in the introduction of ballast in new track.

A still further object of the invention is to provide a rail fastening of the character described so constructed that it may serve 40 as a temporary means for holding bed-plates to ties during track laying with chairs.

Other objects will appear in the course of the following description.

The invention is illustrated in the accompanying drawings, wherein:—

Figure 1 is a perspective view of one end of a tie, a rail thereon, and the improved chair and fastening mechanism; Fig. 2 is an elevation of a portion of the tie and the 50 fastening mechanism, the rail being in section; and Fig. 3 is an end elevation of the fastening and tie.

Corresponding and like parts are referred to in the following description and indi-

cated in all the views of the accompanying drawings by the same reference characters.

Referring to these figures, A designates a tie which may be of any ordinary form, and which is illustrated as a wood tie. 55

B designates a rail which may be of any standard cross section.

Disposed upon the tie is a bed plate 2 which has the form of a channel beam, this base plate being formed with an upwardly 60 extending flange or abutment 3 at each end, the inner faces of these flanges or abutments being inwardly beveled, as at 4. This bed plate has a width between the flanges or abutments 3 greater than that of the rail. 65

Disposed between the abutments or flanges 3 and the base of the rail are rail clamping members which also constitute rail braces. There are two of these members on each side of the rail. Each member comprises a web 70

5 having a height at its inner end preferably equal to the distance between the base flange of the rail and the head thereof, as shown in Fig. 2. The upper edge of this web 5 extends downwardly and outwardly. 75 The lower edge extends horizontally a distance equal to the width of the base flange of the rail and then the material of which the rail brace is formed is bent at right angles, as at 6, and extended horizontally 80 for a distance, and then bent downwardly, as at 7, the inner face of this downwardly bent portion being formed with horizontally disposed teeth 8 constituting a gripping surface. The width of the portion 85 6 of each rail brace is equal to the distance between the edge of the base flange of the rail and the lower margin of the inner face of the abutment 3.

The outer edge face 9 of the portion 5 is 90 downwardly and inwardly beveled, the inclination of this edge face being approximately the same as the inclination of the inner face of the corresponding abutment 3. As before stated, there are two of these rail 95 engaging members on each side of the rail, said members having portions 6 extending in opposite directions so that the tie is embraced between the downwardly extending portions 7. The rail clamping members or 100 braces 5 are adapted to be drawn together by means of a bolt 10 which passes through the rail braces, said bolt being provided with a washer 11 and with a nut 12.

The operation of this invention will be obvious from the drawing. When it is desired to attach the rail to a tie, the rail braces are disposed against the web of the rail and then shifted toward each other, in the position shown in Fig. 1, until the portions 7 of the rail braces are in contact with the side faces of the tie. The rail braces are then drawn together by means of the bolts 10 and the teeth 8 forced into the tie. Inasmuch as the teeth 8 bite into the tie, the bed plate 2 will be held firmly down upon the tie and the rail B will be held firmly upon the bed plate. It will be seen that no accidental displacement of the rail can occur for the reason that the outer edge of each rail brace bears against the corresponding abutment 3. When the rail braces are clamped by the bolts 10 and the teeth 8 are forced firmly into the tie, it is impossible to shift the rail braces upwardly or laterally. The bolt receiving holes are preferably of sufficient diameter to permit the bolts 10 to be readily driven out when desired. It is obvious, however, that, if it be desired to raise the rail, a shim may be inserted between the rail and the bed plate and the rail braces again clamped to the tie.

While, of course, this form of fastening may be used for permanently connecting the rail to the tie, where desirable or necessary, it is obvious that the principal use of the invention will be in temporarily fastening the rail to the tie to provide for an adjustment of the rail while the sub-structure and ballast are in a disturbed condition in construction periods.

It will be obvious that the invention may be very cheaply made; that the parts interlock with each other; that the base plate cannot shift, and that the rail cannot shift with relation to the base plate. The abutments of the bed plate perform the dual function of holding the rail to gage in the different positions of said rail, and as a means for supporting the rail braces in a truss-like manner, thus preventing buckling of the bed plate downwardly at its center and curling upwardly at its edges and permitting the employment of a bed plate of ordinary thickness. It will further be plain that this form of rail bracing, fastening and chair conforms to the requirements of the official report of the Block Signal and Train Control Board of the Interstate Commerce Commission, in that it provides means for supporting the rail against tipping thrust, as well as supporting the rail against horizontal and vertical thrusts, and that it provides for a vertical adjustment of the rail by means of shims. It will further be seen that it will be relatively easy to release these fastenings and insert a shim beneath the rail and then re-apply the fastenings so that

such re-adjustment does not require the services of a section gang with special tools.

Having thus described the invention, what is claimed as new is:—

1. A rail fastening comprising a bed-plate, opposed pairs of members co-acting with the bed-plate and adapted to engage the web of a rail, each of said members at its outer end being laterally extended and then downwardly bent, the downwardly bent portions being provided with gripping faces, and means for drawing the members of each pair toward each other whereby to force the gripping faces into a tie and holding the bed-plate against displacement. 80

2. A rail fastening including a bed-plate, opposed pairs of members co-acting with the bed-plate and engageable with the base and web of a rail, each of said members having a downwardly extending portion formed on its inner face with teeth adapted to engage the side face of a tie, and means for drawing the members of each pair toward each other to cause the teeth to bite into a tie and holding the bed-plate against displacement. 85

3. A rail fastening including pairs of oppositely disposed rail braces adapted to engage with the head, web and base flange of a rail, each of said rail braces at its outer end being laterally extended, the lateral extension of one brace being oppositely directed with relation to the lateral extension of the other brace on the same side, the ends of the lateral extensions being downwardly bent and formed upon their inner faces with teeth, said rail braces being perforated, and bolts passing through the perforations and having nuts whereby the rail braces of each pair may be drawn toward each other and the teeth forced into the side faces of a tie. 105

4. A rail fastening comprising a bed plate having upwardly extending abutments at its ends, oppositely disposed pairs of rail braces disposed between said abutments and extending at substantially right angles thereto, the inner ends of said rail braces being adapted to engage between the head and base of a rail, each of said rail braces of a pair having lateral extensions, the ends of said lateral extensions being downwardly bent, the downwardly bent portions being formed with gripping faces, and means for drawing the rail braces of each pair toward each other to hold the bed-plate on a tie and cause the gripping faces to engage the side of said tie. 110

5. A rail fastening comprising a bed plate having upwardly extending abutments, the inner faces of which are downwardly and inwardly inclined, oppositely disposed pairs of rail braces disposed between said abutments and extending at substantially right angles thereto, the inner ends of said rail braces being adapted to engage between the head and base of a rail and the outer end faces thereof 125 130

being downwardly and inwardly inclined to co-act with the inclined faces of the abutments, each of said rail braces of a pair having lateral extensions, the ends of said lateral extensions being downwardly bent, the inner faces of the downwardly bent portions being formed with teeth, and means for drawing the rail braces of each pair toward each other to cause the teeth to engage the side face of a tie.

6. The combination with a tie and a rail, of a bed plate supported on the tie and having upwardly extending abutments, oppositely disposed pairs of rail braces having wedging engagement with the inner faces of the abutments and engaging between the head and face of the rail, each rail brace having a lateral extension of a width equal to the distance between the edge of the base flange of the rail and the adjacent abutment, the ends of said extensions projecting beyond the edge of the bed plate and being downwardly bent, and provided with gripping faces, and means for drawing the rail braces of each pair toward each other to cause the gripping faces on said extensions to engage the tie.

7. A rail fastening including oppositely disposed pairs of members engageable with the base and web of a rail, each member of each pair having a downwardly extending portion provided with a gripping face for engagement with a tie, and means for drawing the members of each pair toward each other to cause the gripping faces to bite into the tie.

8. A rail fastening including a chair adapted to receive a rail and to permit said rail to be adjusted vertically with respect thereto, and means for clamping the chair to a cross tie and holding the rail in different positions of vertical adjustment.

9. The combination with a tie and rail, of a bed plate resting on the tie and provided with spaced abutments, and means co-acting with the rail and abutments for clamping the rail on the bed plate or on a shim and said bed plate to a cross tie.

10. The combination with a tie, of a chair adjustable longitudinally of the tie, a rail adjustable vertically with respect to the chair, and means for clamping the rail in different positions of vertical adjustment on the chair and the chair in adjusted position on the tie.

11. The combination with a tie, of a chair resting on the tie and adjustable longitudinally thereof, a rail adjustable vertically with respect to the chair, and means for simultaneously clamping the rail in adjusted position on the chair and the chair on the tie.

12. The combination with a bed plate, of a rail resting directly on the bed plate or on a shim and adjustable vertically with respect thereto, and means for clamping the bed plate on a tie and holding the rail in different positions of vertical adjustment.

13. The combination with a tie and a rail, of a chair adapted to receive the rail and adjustable longitudinally of the tie, said rail being adjustable vertically without disturbing the chair and laterally with the chair, and means for clamping the chair in adjusted position on the tie and the rail in adjusted position on the chair.

14. A rail fastener including a chair having an upstanding abutment and provided with a seat adapted to receive a rail, and clamping members interposed between the base of the rail and the abutment and having upstanding portions bearing against the web of the rail and depending portions provided with gripping faces for engagement with the adjacent sides of a cross tie, and means piercing the upstanding portions of the clamping members for forcing the gripping faces thereof into engagement with said cross tie.

In testimony whereof I affix my signature in presence of two witnesses.
